UNITED STATES PATENT OFFICE.

HERMAN C. MAISE, OF SPRINGFIELD, MASSACHUSETTS, ASSIGNOR, BY MESNE ASSIGNMENTS, TO EDWARD G. BUDD MANUFACTURING COMPANY, A CORPORATION OF PENNSYLVANIA.

DESIGN FOR A VEHICLE-BODY.

54,646.

Specification for Design.

Patented Mar. 9, 1920.

Application filed September 7, 1916. Serial No. 118,926. Term of patent 14 years.

To all whom it may concern:

Be it known that I, HERMAN C. MAISE, a citizen of the United States, and a resident of Springfield, county of Hampden, and State of Massachusetts, have invented a new, original, and ornamental Design for Vehicle-Bodies, of which the following is a specification, reference being had to the accompanying drawing, forming a part thereof.

The drawing is a side elevation of a vehicle body constructed in accordance with my improved design.

This body includes a transverse window frame A, which is inclined upwardly and rearwardly and extends in the form of a plain surface transversely across the front

end of the body at right angles to the center line thereof. A rigid back B in conjunction with the frame A supports a permanent roof C. Windows D are supported by the body proper while a window E is carried by the door F and is disposed between the windows D, thus imparting to the side of the body a paneled effect, the forward panel being of irregular shape in outline. At its lower rear portion the body is formed with a curved surface as shown which usually is inset from the side surface of the body to form a wheel housing.

I claim:

The ornamental design for a vehicle body as shown and described.

HERMAN C. MAISE.
